UNITED STATES PATENT OFFICE.

GEORGE S. SOWERS, OF SPRING HILL, KANSAS.

GRAIN AND STOCK RACK.

1,333,879.

Specification of Letters Patent. Patented Mar. 16, 1920.

Application filed June 10, 1918. Serial No. 239,280.

To all whom it may concern:

Be it known that I, GEORGE S. SOWERS, a citizen of the United States, residing at Spring Hill, in the county of Johnson, State 5 of Kansas, have invented certain new and useful Improvements in Grain and Stock Racks, of which the following is a full and exact specification.

The present invention relates to grain and 10 stock racks, and one of the principal objects of the invention is to provide an improved adjustable rack construction which will adapt the same for use for either stock or grain hauling purposes and also permit 15 of the sides of the rack being either entirely dispensed with for certain kinds of hauling, or readily and conveniently adjusted to different heights as the rack is being loaded or unloaded.

20 It is also sought to provide an adjustable rack of the character described in which the side bars inclosing the sides of the rack are provided with improved means for detachably mounting the same in their normal position of use, and also with means for retaining said side bars (when not in use) in compactly assembled relation at the opposite sides of the rack.

A further object of the invention is to 30 provide an improved stock chute construction in connection with the rear end of the rack, and embodying a movable gate member adapted to act either as a gate, when in upright position, or as the floor of a chute 35 when in lowered position; and associated with this gate member is a pair of grate members adapted to be removably mounted at the sides of said gate member and also provided with means for detachably suspending the same from the sides of the rack whenever the chute construction is not required.

40 It is also sought to provide a neat, simple, and inexpensive construction of this type, 45 and which will comprise as few parts as possible and yet be strong and durable, as well as economical to manufacture.

With these general objects in view, as well 50 as minor objects as will appear in the course of the detailed description, the invention will now be described with reference to the accompanying drawings illustrating one form of embodiment of the improvements, after which the novel features therein will

be set forth and defined in the appended 55 claims.

In the drawings—

Figure 1 is a perspective view of a wagon equipped with a grain and stock rack constructed in accordance with the present invention, and showing the stock chute formation at the rear end of the rack;

Figs. 2 and 3 are side and rear end views, respectively, of the same, but illustrating the rear end of the rack as closed and the 65 sides of the stock chute suspended from the sides of the rack;

Fig. 4 is a side elevation similar to Fig. 2, but showing the side bars of the rack demounted and assembled at the bottom of the 70 rack;

Fig. 5 is an enlarged and broken perspective view of one of the side rail supporting brackets;

Fig. 6 is a perspective view of the end portion 75 of one of the side rails and illustrating the cross-bar element for engagement with the supporting bracket for the purpose of preventing endwise movement of the rail;

Fig. 7 is a perspective view of a rail end 80 portion illustrating another form of bracket-engaging means for preventing endwise movement of the rail;

Fig. 8 is a perspective view of a modified form of construction for connecting the side 85 rails and the rack standards, showing the parts in disengaged relation; and

Fig. 9 is a perspective view of a further modified form of construction for connecting the side rails with the standards, with 90 the parts shown in engaged or connected relation.

Referring to the drawings in detail, I have illustrated therein a running gear 10 which may be of any approved or preferred 95 type of construction, having the bolsters 12 thereof carrying the beams 14 which support the flooring 16 that forms the bed of the rack body. Each side of the rack bed is provided with a stiffening strip 18 which is 100 applied to the ends of the flooring 16 as shown in Fig. 1. At each end of the rack is mounted a series of uprights or standards, comprising the corner standards 20, and intermediate standards 22, each being secured 105 to the rack bed in upright position by means of angle brackets 24. For inclosing the rack at the ends, a series of cross strips or boards

26 are secured to the front standards 20, 22, in spaced relation, and a similar series of short cross strips 28 is secured to the rear standards and connect the corner standards 5 with their adjacent intermediate standards, but leave a gateway between said rear intermediate standards 22.

Mounted between the rear standards 22 for closing said gateway is a gate member 10 30 of strong construction, provided with hinge elements 32 (see Fig. 3) for pivotal connection with the rear edge of the rack bed, and adapted to allow said gate 30 to swing from upright position as illustrated 15 in Fig. 3, to lower horizontal (Fig. 1) or more or less inclined position as conditions may require, so as to form the floor of a stock chute leading to the rear end of the rack and communicating with said gateway 20 when the construction is operated as a stock rack. Hooks 34 provided on the gate, and co-operating with eyes or staples 36 on said uprights 22, or any equivalent latching means, may be employed for retaining said 25 gate in upright position.

A set of side bars 40 is provided at each side of the rack for spanning the space between the front and rear uprights or standards 20, when it is desired to have the sides 30 of the rack inclosed. As it is one of the main objects of this invention to enable these side bars to be placed in position or taken down at will and with a minimum of trouble and loss of time, I provide each of 35 the corner standards 20 with a series of bracket pieces, designated generally by the reference numerals 42, and which may be conveniently stamped from sheet metal to form flanges 44 adapted to be secured to the 40 standards in any suitable manner. Each bracket 42 is shaped to form in effect a socket closed at one end by the face of the standard, and open at its other end, and also open at the top for permitting the ends of 45 the side bars to be simply dropped down into place within the brackets. The brackets being mounted on the inner opposed faces of the corner standards, the latter abut against the ends of the side bars 40 and 50 normally serve to restrict any endwise movement of the side bars, while the side walls of said brackets obviously prevent any lateral movement of the side bars 40.

Where the character of the load is such as 55 to tend to bow the side bars 40 outwardly and thus cause an endwise slipping of the ends of the side bars within the brackets, additional security may be desired for retaining the ends of the side bars in position. 60 One of the means which may be employed for this purpose comprises bolts 45 as shown in Figs. 1 and 2, which bolts are passed through the ends of the side bars and through registering bolt openings 46 formed 65 in the side walls of the brackets 42 (see Fig.

4). Or, as illustrated in Figs. 1, 2, 4 and 5, the brackets may be formed with notches 48 in their upper edges, adapted to receive the projecting ends of cross plates 50 secured to the ends of the side bars 40, which construction will obviously hold the side bars firmly in fixed relation to the brackets. Again, this object may be attained by providing each of the brackets 42 with a bottom opening 52 adapted to receive a fixed projection 70 75 54, such as formed by the head of a bolt or the like, secured to the bottom face of the side bar and adjacent to each end thereof, as shown in Fig. 7.

In Fig. 8 is also illustrated a modified construction for accomplishing this purpose, the side bars being provided at each end with a plate 56 having a projecting portion or tenon 57 adapted to be received in the eye of an eye-bolt 58 secured to the standard 80 in lieu of the specific form of bracket 42 already described. A very similar arrangement is set forth in Fig. 9, in which the side bar 40 has each of its ends fitted with a block 60 formed with a tenon projection 61 85 adapted to be received in a mortise bracket 62 carried by the standard.

Each of the forms of construction above described for connecting the side bars 40 with the corner standards serves the essential purpose of removably supporting and retaining the side bars against lateral movement as well as against endwise movement, by virtue of their being not only provided with means in positive engagement with said brackets but also by the side bars being held with their ends in abutment with the inner opposed faces of the standards. 95

The construction above described of course aims to dispense with any side standards or 100 uprights intermediate the corner standards 20, and for most purposes will be found adequate; but I contemplate using, as an additional security in some instances, an intermediate upright 64 at each side of the rack, 105 these two uprights 64 being simply bolted, as at 66 (see Fig. 2) to the top side bars 40 and provided with foot tenons adapted to be fitted through mortise openings 70 in extensions 72 of the flooring 16 projecting from 110 the opposite sides of the rack bed.

At each of the corners of the rack bed, a retaining device is provided for receiving the ends of the side rails 40 when they are demounted from the corner standards and 115 piled in assembled relation on the rack bed as shown in Fig. 4. Each of these retaining devices comprises a receptacle structure, including a bottom 74 formed by an extension of the flooring 16, and also an outer side wall 76 and end wall 78, while one of the angle brackets, 24, of each standard 20 is formed with a web plate 80 to provide an inner side wall for the corresponding retaining device. Thus means is provided for 120 125 130

supporting the ends of the side bars or rails when in demounted position, their midportions being supported by the extensions 72 above referred to; and in this position, as 5 illustrated in Fig. 4, the side rails are retained against any tendency to either lateral or endwise movement, as will be readily understood.

A strap iron step 82 may be conveniently 10 attached by securing it in position at opposite sides of one of the extensions 72.

When the gate 30 is let down to form the floor of a stock chute, as already referred to, means is provided for forming the sides of 15 the chute, as illustrated in Fig. 1, and for this purpose I provide a pair of side grate members made up of vertical pieces 84 connected by horizontal cross strips 86. The lower ends of the vertical pieces 84 are 20 formed with tenons 84' (see Fig. 2) for fitting in a pair of mortise irons 88 secured to each of the opposite side edges of the gate 30. In most of the positions of the chute as thus constructed it will be apparent that the 25 side grate members will be securely supported by the mortise irons 88, and the front ends of the cross strips 86 will be engaged by the sides of the gateway formed by the intermediate rear uprights or standards 22 30 and thereby retained sufficiently firmly, for all practical purposes, against any lateral outward movement. The grate members are further provided with hook elements 90 adapted to hook over the top side bars or 35 rails 40 for suspending the said grate members therefrom (see Figs. 2 and 3) when the chute structure is not required, the gate 30 being simply closed by swinging the same up into upright position and latching it as 40 already explained.

Having described the invention, what I claim as new and desire to secure by Letters-Patent, is:

1. A grain and stock rack construction 45 comprising a rack bed, corner standards carried by said bed, a series of side bars for each side of the rack, and means for detachably connecting the ends of said side bars

to the standards with the ends of the side bars abutting against the inner opposed 50 faces of the standards.

2. A grain and stock rack construction comprising a rack bed, corner standards carried by said bed, a series of side bars for each side of the rack, and brackets carried 55 by the inner opposed faces of said standards and forming sockets for removably receiving and supporting the ends of said side bars in abutment with the said opposed faces of the standards while preventing any 60 lateral movement of the ends of said side bars.

3. A grain and stock rack construction comprising a rack bed, corner standards carried by said bed, a series of side bars for 65 each side of the rack, brackets carried by said standards and forming sockets for removably receiving and supporting the ends of said side bars and preventing lateral movement thereof, and means for preventing 70 endwise movement of said side bars within said brackets.

4. A grain and stock rack construction comprising a rack bed, corner standards carried by said bed, a series of side bars for 75 each side of the rack, means for detachably connecting the ends of said side bars to said standards, and means for removably receiving and retaining said side bars in assembled relation at the bottoms of said standards on opposite sides of said bed.

5. A grain and stock rack construction comprising a rack bed, corner standards carried by said bed, a series of side bars for each side of the rack, means for detachably 85 connecting the ends of said side bars to said standards, and a side bar retaining device at each corner of the bed, said retaining devices being shaped to receive the ends of said side bars and support the same in assembled relation at the bottoms of said standards and serving to retain said bars against either lateral or endwise movement.

In witness whereof I hereto affix my signature.

GEORGE S. SOWERS.
